A hand-drawn diagram of a graduated glass tube, likely a thermometer. The tube is vertical with a bulb at the bottom. It has several horizontal markings: a small tick mark at the top labeled '5', a larger tick mark labeled '15' with a vertical line through it, a tick mark labeled '20' with a vertical line through it, a tick mark labeled '24' with a vertical line through it, and a large tick mark labeled '28' with a vertical line through it. The tube is set into a rectangular base with a square cutout in the center.

ATTORNEYS

UNITED STATES PATENT OFFICE.

WILLIAM MACALLASTER BARBOUR, OF ROANOKE, VIRGINIA.

LOW-WATER ALARM FOR BOILERS.

Application filed April 16, 1924. Serial No. 707,011.

To all whom it may concern:

Be it known that I, WILLIAM M. BARBOUR, a citizen of the United States, residing at Roanoke, in the county of Roanoke, State 5 of Virginia, have invented certain new and useful Improvements in Low-Water Alarms for Boilers, of which the following is a specification.

My invention is a low water alarm for 10 steam boilers, and it consists in the combinations, constructions, and arrangements herein described and claimed.

An object of the invention is to provide 15 a simple and reliable device which is adapted for attachment to a steam boiler of substantially conventional construction and which is adapted to be actuated when the water within the boiler falls to a definite level to give an audible signal.

20 A further object of the invention is to provide an attachment of the character described which will not interfere with the operation of the boiler to which it is applied in an ordinary manner and which is thoroughly practical commercially.

25 Other objects and advantages will be apparent from the following description, considered in conjunction with the accompanying drawings, in which:

30 Figure 1 is a longitudinal section through a portion of a steam boiler and through an attachment embodying the invention with which the boiler is equipped.

Figure 2 is a plan view of the attachment 35 with the signal alarm thereof omitted.

Figure 3 is a transverse vertical section through a portion of the upper wall of the boiler and through the attachment, the view being taken substantially on the line 3—3 of

40 Figure 1, with the signal alarm omitted.

Figure 4 is a perspective view showing a valve and valve stem construction which is comprised in the device, and

45 Figure 5 is a relatively enlarged section along the line 5—5 of Figure 4.

In Figure 1, the numeral 1 designates a steam boiler generally. Only a portion of the boiler is shown. As is usual, the boiler is provided with a water chamber 2 which 50 extends below the level of the crown sheet 3 for the fire-box 4 of the boiler. It, of course, is desirable that means be provided for apprising an interested person that the level of water within the chamber 2 of the boiler is relatively low since otherwise the continued operation of the boiler without an

additional quantity of water being supplied thereto may result in injury to the boiler and to the structure adjacent thereto. My invention contemplates the provision of 60 means which will act automatically when the water within the boiler falls to a definite level to sound an audible alarm.

In carrying out my invention, I provide a 65 box-like casing 5 which is supported upon the boiler top and which defines a chamber 6. The chamber 6 has communication with the water chamber 2 of the boiler through a drain pipe 7 which opens at its upper end through the bottom of the casing 5 and depends within the water chamber 2 below the level of the crown sheet 3. The chamber 6 also has communication with the chamber 2 through a pipe 8 which extends vertically 70 through the bottom of the casing 5 and terminates at its upper end adjacent to but short of the top wall of the casing 5. The pipe 8 depends within the water chamber 2 and terminates at its lower end at a slight distance above the level of the crown sheet 3. 75

The chamber 6 serves as a float chamber. A float 9 is supported therein by being attached pivotally to one end of a float lever 10 which is pivotally supported at its other end on a horizontal pivot element 11 which is carried by lugs 12 depending from the top of the casing 5 adjacent to one end of the latter. The float 9 thus is adapted to move vertically within the chamber 6 in accordance with the rise and fall of liquid therein. 80 A vertical guide 13 depends from the top of the casing 5 and has a vertical slot 14 in which the float arm 10 may move, the engagement of the guide 13 with the float arm being adjacent to the free end of the latter. 85

The top of the casing 5 is provided with a threaded opening 15 in which is screwed the lower end portion of a tubular valve casing 16. The bore of the valve casing 16 is reduced in diameter adjacent to its lower end, as at 17, to rather closely engage with a longitudinally slotted valve stem 18 which extends slidably therethrough. The portion of the valve casing that is reduced in inner diameter is fashioned at its lower end, as at 19, to provide a seat for a downwardly opening tapering valve disc 20. The stem 18 extends through the bore of a tubular boss 21 which is upstanding from the valve casing and the upper end portion of the valve stem carries a nut 22 which is in threaded engagement therewith. An expansion spring 100 105 110

23 is arranged on the tubular boss 21 between the valve casing and the nut 22 and re-acts against the latter in such manner as to tend to force the valve stem slidably upward until the valve 20 has been moved against the seat therefor and to position to prevent flow of fluid from the chamber 6 into the valve chamber 16.

5 The valve 20 has a pendent axial extension 10 24 which is enlarged and fashioned in loop form at the lower end thereof, as indicated at 25. The float arm 10 extends through the loop 25 and engages with the lower end of the latter in such manner as to force the 15 valve 20 downward and away from its seat when the float 9 is in lowered position, as illustrated in Figure 1.

20 The valve casing 16 is provided with a tubular lateral outlet 26 adapted for connection with the conduit 27 leading to a whistle 28 or other suitable signal of known type of construction and adapted to be actuated when pressure fluid is supplied thereto.

25 A by-pass conduit 29 may connect the upper part of the float chamber 6 with the upper part of the water chamber 2 of the boiler and may be provided with a valve 30 of ordinary construction.

30 The top of the casing 5 may be provided with clean-out openings normally closed by threaded plugs, as indicated at 31.

35 From the foregoing description of the various parts of the device, the operation thereof will be readily understood. Let us assume that the water chamber 2 of the boiler is filled to a level above the lower end of the pipe 8 and the valve 30 is closed. The steam pressure within the boiler will 40 have caused water to rise through the pipes 7 and 8 and to flow into the float chamber 6 so that the float 9 will be moved upward and the weight of the float and of the float arm 10 will be removed from the loop which 45 depends from the valve 20 so that the spring 23 will be permitted to function to return the valve 20 to closed position. When the level of the water within the chamber 2

falls below the lower end of the pipe 8, the pressure fluid from the boiler will pass 50 through the pipe 8 into the float chamber and the pressure within the float chamber and the boiler will be equalized and, therefore, water will be drained from the chamber 6 through the pipe 7 and the float 9 55 will fall in response to the lowering of the water level within the float chamber, thereby causing movement of the valve 20 from its seat. The pressure fluid within the float 60 6 then will escape through the valve casing 16 to the whistle 28 and will cause the latter to be actuated, whereby an audible signal will be given.

Obviously, my invention is susceptible of embodiment in forms other than that which is illustrated in the accompanying drawings, and I, therefore, consider as my own all modifications and adaptations that fairly fall within the scope of the appended claim.

65 The by-pass 29 and valve 30 are provided 70 to facilitate the testing of the device.

I claim:

The combination with a boiler, of a casing superimposed on the boiler, said casing having an outlet adapted for connection with a whistle, a downwardly opening valve controlling said outlet and spring-pressed toward closed position, a float, means adapted to be actuated on downward movement of said float to move said valve from closed position, a pipe establishing communication between the water chamber of the boiler and the interior of said casing, said pipe terminating at its upper end at a considerable distance above the level of the bottom 75 of the casing and terminating at its lower end slightly above the level of the crown sheet of the boiler, a second pipe opening at its upper end through the bottom of the casing and depending within the water chamber to terminate at its lower end below the level of the crown sheet of the boiler, and a valved by-pass conduit connecting the upper part of said casing with the upper 80 part of said boiler.
